Primary Examiner — Elizabeth J Oswecki(74) Attorney, Agent, or Firm — Griffiths & Seaton PLLC(57) CLAIM

The ornamental design for a glass holder, as shown and described.

DESCRIPTION

FIG. 1 is a rear, perspective view of a glass holder showing our new design;

FIG. 2 is a rear view thereof;

FIG. 3 is a front view thereof;

FIG. 4 is a right side view thereof;

FIG. 5 is a left side view thereof;

FIG. 6 is a top view thereof;

FIG. 7 is a bottom view thereof;

FIG. 8 is a rear, perspective view of the glass holder of FIG. 1 with portions of the environmental subject matter removed to clearly illustrate the claimed design;

FIG. 9 is a rear view thereof;

FIG. 10 is a front view thereof;

FIG. 11 is a right side view thereof;

FIG. 12 is a left side view thereof;

FIG. 13 is a top view thereof; and,

FIG. 14 is a bottom view thereof.

The features shown in broken lines depict environmental subject matter only and form no part of the claimed design.
